UNITED STATES PATENT OFFICE.

LEMUEL E. GARNETT, OF TACOMA, WASHINGTON.

JEWEL-SETTING MACHINE.

1,415,235.

Specification of Letters Patent. Patented May 9, 1922.

Application filed May 18, 1920. Serial No. 382,367.

To all whom it may concern:

Be it known that I, LEMUEL E. GARNETT, a citizen of the United States, and resident of the city of Tacoma, county of Pierce, and

5 State of Washington, have invented certain new and useful Improvements in Jewel-Setting Machines, of which the following is a specification.

This invention relates to improvements in 10 jewel setting machines, and more particularly to machines of that character especially adapted to the work required in the making or repairing of watches; the principal object of the invention being to provide a machine 15 which will be simple and efficient in its operation, durable in construction, which will be relatively inexpensive and which will, by its use, greatly expedite the work for which it was intended.

20 It is also the object of the invention to provide a machine of the above character, comprising a lathe or chucking spindle, wherein pieces used for jewel mountings, or the like, may be held in position to be worked upon, and to provide a revoluble 25 turret whereon various forms of cutting, burnishing or polishing tools are mounted in positions to be moved by selective adjustment and rotation of the turret into working 30 relation with the pieces that may be held in the lathe chuck.

A further object of the invention resides in the provision of the several features of adjustment for properly setting and adjusting the various tools carried by the turret.

35 In accomplishing these and other objects of the invention, I have provided the improved details of construction, the preferred forms of which are illustrated in the accompanying drawings, wherein—

40 Figure 1 is a side view of a jewel setting machine constructed according to the present invention.

Figure 2 is a plan view of the same.

45 Figure 3 is a transverse vertical section of the machine, taken on the line 3—3 of Figure 2, particularly illustrating the construction of the lathe spindle, and the manner of mounting a working tool in the revoluble turret.

50 Figure 4 is a fragmental plan view of the device, illustrating one of the stationary cutters, and mechanism for making small adjustments of the turret.

55 Figure 5 is a back side view of the turret adjusting mechanism.

Figure 6 is a plan view of the stationary cutters and jewel and tool setting gauge.

Figure 7 is an elevation of the table and a cutter, looking in the direction of the arrow in Figure 6, showing the cutter adjusting screw.

Figure 8 is a detail sectional view of the turret head, showing the screw whereby it is locked to the adjusting plate.

Referring more in detail to the drawings, 65 wherein like reference numerals designate like parts—

1 and 2, respectively, designate upper and lower, horizontally disposed, circular tables which are rigidly spaced apart by three 70 equally spaced posts 3, and are supported at a desirable working height by legs 4 which are fixed to the lower table and at their ends are equipped with screws 5, whereby the device may be secured to a table 75 or other working foundation.

Revolubly mounted at its opposite ends in the tables 1 and 2, is a lathe spindle 6, provided at its upper end with a conically tapered shoulder 7 which seats against an 80 opposing shoulder in a central opening 8 in the table 1, and at its lower end has a downwardly facing, conically tapered shoulder 9 which seats within a conically tapered opening in a nut 10 threaded centrally 85 through the table 2, and adjustable therein to take up any wear that is incidental to use of the machine, and which is equipped with a lock nut 11 that may be tightened against the table to retain the adjustment.

The spindle 6 has a longitudinal bore 12 90 therein, wherein the shank of a tubular chuck 13 is extended. At its upper end the chuck has a longitudinally split head 14 which seats against a conical bore 15 at the 95 upper end of the spindle bore 12, and at its lower end is threaded into a holding stem 16 that is projected into the spindle bore, with a wheel or head 17 fixed thereon, which seats against the lower end of the spindle 6 and which may be turned to loosen the chuck, or to draw it inwardly to contract the split head against a piece, or wire that may be extended into the chuck, to hold the same while being worked on.

100 Mounted on the spindle is a grooved pulley wheel 20 over which a belt 21 may be extended and driven in any suitable manner to revolve the spindle for the purpose of turning or cutting pieces held by the chuck.

Extending laterally from the table 1 is a bracket 22 having a vertical portion 23 and a forwardly directed arm 24, overlying the table, and supported on the arm 24 in

superimposed and concentric relation, is a circular plate 25 and a turret plate 26. A bolt 27 is extended upwardly, through the arm, and centrally through the plate 25 and 5 turret to support the same revolvably on the bracket; the turret, which is supported on the plate, has a boss 28 on its upper side which serves as a hub for the bolt, and the latter extends above the boss and has a nut 10 29 threaded thereon to hold the turret substantially in working position.

Mounted in the turret, at equal radial distances from the bolt, about which it revolves, are a plurality of tool carrying devices 30, each of which may, on revolving the turret, be brought into alignment with the axial line of the spindle 6 to position tools carried thereby in working relation to pieces of metal, wire or plates that may be 15 held by the chuck head 14, or on the base plate 2. The tool holding devices 30 comprise tubular members 31 that are fixed to extend vertically through the turret with their lower ends open and their upper ends 20 closed by caps 32. Within the tubular members 31 are blocks 33, each provided with a threaded stem 34 that extends upwardly through an opening in the tube cap and at 25 their upper ends have heads 35 thereon whereby the stems may be lifted to move the block upwardly against the pressure of spring 36 located within the tubes and bearing against the caps and block.

Each block 33 has a tapered tool socket 35 38 in its lower end for receiving a tool, such as the cutter 39, the burnisher 40, polisher 41, or other desirable tools.

Threaded onto the stems between the caps 32 and heads 35 are nuts 43, which may be 40 adjusted to limit the downward movement of the tools to a certain distance. These nuts, as is shown in Figure 3, are graduated in degree marks, which may be observed when adjustment is made and will serve to 45 facilitate re-setting or adjustment.

Extending downwardly from the rear edge of the plate 25 is an arm 45 having a laterally turned end 46, as shown in Figures 1 and 4, and fixed beneath the bracket 22 is 50 an arm 47 which extends rearwardly beneath the arm 45, and at its outer end has an upturned, bifurcated, portion 48, wherein a block 49 is transversely adjustable; the block being slidable on a cross rod 50 and threaded onto an adjusting screw 51, which may be turned by a head 52 to adjust the block laterally. Pivotaly fixed by a pin 53 to the underside of the block 49, is a head 54, and slidable therein is a pin which at its inner end is threaded into the out-turned end 55 46 of the arm 45.

Threaded downwardly through the turret plate 26 is a thumb screw 56, having a tapered inner end 47 which is adapted to seat 60 in any one of a plurality of tapered sockets

57 in the upper surface of the plate 25; the sockets being spaced apart at angular distances about the bolt 27, which correspond to the angular spacing of the tools carried by the turret and are at such position on the 70 plate 25 that when the screw 56 is in locking position in the different sockets, the tools will be held in co-axial alinement with the lathe spindle, and should slight adjustment of the tool in use be desired or necessary, this is 75 accomplished by lateral shifting of the block 49 by means of the screw 51.

After a desired adjustment of the block 49 has once been made, it can be locked by set screws 60 and 61, that are threaded 80 inwardly from opposite sides of the bifurcated end of the arm 47.

Mounted on the table, or plate 1, is a gauge bar 60, which is pivoted at its inner end to the table by a pivot pin 61, and at its 85 opposite end is adapted to move toward or from a stop block 62 fixed on the forward edge of the table. The bar has a raised central portion 63, which permits it to overlie and move freely across plates, or pieces, that 90 may be fixed on the table, as is shown in Figure 6, and at its movable end has a slotted, laterally extending arm 64, through which a set screw 65 is threaded into the edge of the table to hold the bar at any ad- 95 justed or set position.

In this construction, the distance from the pivot pin 61 to the center of the spindle chuck is equal to the distance from the chuck to the stop block, and when the swinging end 100 of the bar is engaged with the block, its inner edge designated by numeral 66 bisects the axial line of the spindle, for a purpose presently described.

Mounted within openings 67, cut in the 105 table 2, are frames 68, pivotally mounted at one edge, as by the pins 69, and adjustable vertically at their opposite edges by screws 70, that are threaded through brackets 71 fixed to the under side of the table. Slid- 110 able longitudinally within these frames toward and from the spindle, are cutter bars 72, which are adjusted by means of screws 73 fixed revolvably in the frames and threaded into blocks 74 that are fixed to the cutter 115 bars. The inner ends of these cutter bars may be designed for various forms of cutting and are adjusted horizontally and lat- 120 erally by manipulation of the screws 70 and 73 to act on pieces that may be mounted in 125 the lathe chuck.

Assuming that the device is so constructed, in using the same for forming a jewel mounting from a piece of wire or the like, the latter is extended into the chuck and clamped therein with its upper end dis- 130 posed in position to be operated upon by a drill or other tool carried by the turret. To properly gauge the diameter of opening for any special size of jewel to be mounted, the

jewel is placed between the stop block and end of the gauging bar, and the cutter is adjusted, as is shown in Figure 3, against its inner edge.

5 Since the distance from the pivot pin 71 to the tool is one half the distance to the position where the jewel is placed, it is apparent that such adjustment of the cutter will provide for cutting or reaming out a 10 mounting that will be of the same diameter of the jewel and the latter can be easily set therein.

After a jewel has been set in the mounting thus provided, other tools are brought 15 into working relation by turning the turret and the jewel can be burnished, polished and made ready for use without removal from the machine.

The cutters mounted in the table 2 can be 20 adjusted as desired to cut off, or trim pieces held in the lathe, or accomplish other work incident to jewel setting operations.

Having thus described my invention, what I claim as new and desire to protect 25 by Letters Patent, is:

1. A jewel setting device of the character described comprising a supporting base, a lathe spindle operatively mounted in the said base, a work holding chuck applicable 30 to the said spindle, a bracket fixed to and extending from the base, a turret adjusting arm mounted pivotally upon the bracket, a turret supported by the bracket upon said arm, a plurality of tools of different character 35 operatively mounted on the said turret and adapted to be individually positioned by revolving the latter in working relation with pieces that may be held in the lathe chuck, means for securing the turret relative 40 to the arm to retain a selected tool in working position and means for adjusting the arm to effect a finer adjustment of the tool toward or from the work being done.

2. A jewel setting device of the character 45 described comprising a supporting base, a lathe spindle operatively mounted in said base, a work holding chuck applicable to the said spindle, a bracket fixed to and extending from the base, a turret adjusting arm 50 pivotally fixed upon the bracket, a tool turret revolvably fixed on the arm, a plurality of tools of different character adjustably mounted on the turret to be moved individually, by revolving the turret, into working 55 relation to pieces that may be held in the chuck, a locking screw for securing the turret relative to the arm to retain a selected tool in working position, a screw operable to adjust the arm to effect a finer adjustment of the turret to move the working tool 60 transversely to the line of the spindle and means for adjusting the tools longitudinally toward or from the piece being worked upon.

65 3. A jewel setting device of the character

described comprising a supporting base, a lathe spindle operatively mounted and supported vertically in said base, a work holding chuck applicable to the spindle, a bracket member fixed to the said base and having a 70 piece extending above and parallel with the base plate, a pivot pin fixed in said bracket, a turret adjusting plate revolvably mounted on said pin, a turret supported on said adjusting plate and revolvable about said pin, 75 tools of different character fixed in said turret plate and adapted to be individually positioned by revolving the latter in working relation to pieces that may be held by the chuck, means for locking the turret at any 80 adjusted position on the adjusting plate to place a selected tool approximately near its working position, and mechanism supported from the base member for moving the adjusting plate to effect a finer adjustment of 85 the tool with respect to the piece being worked upon.

4. In a device of the character described, in combination, a horizontal base plate, a 90 lathe spindle operatively mounted in said plate, a turret plate operatively mounted to revolve in a plane parallel to and above the plane of the base plate, a plurality of tools fixed in said turret plate at equal radial distances from its axial line and individually 95 movable into the axial line of the spindle and a tool gauging bar pivotally fixed at one end to the base plate and movable at its opposite end along a graduated scale on the base plate and engagable between its ends 100 by a tool of the turret when the said tool is moved into working alinement with the spindle.

5. In a device of the character described, in combination, a horizontal base plate, a 105 lathe spindle having its upper end revolvably fixed in said base plate, a turret plate mounted to revolve in a plane parallel to and above the base plate, a plurality of tools mounted in said turret to be moved individually into the axial line of the spindle, a tool gauging bar pivotally mounted on the base plate in the plane of the axial lines of the turret and spindle and movable at its 110 opposite end along a graduated scale on the base, said bar having an upwardly offset central portion adapted to overlie pieces held in the lathe spindle and to be engaged by tools moved into working relation to said pieces, for the purpose set forth. 115

6. A combination as set forth in claim 5 wherein the distance from to pivot point of the gauge bar to the circular line of travel of the various tools is equal to one-half the distance from the pivot point to the line of 120 the graduated scale, for the purpose set forth.

Signed at Tacoma, Washington, this 11th day of May, 1920.

LEMUEL E. GARNETT.
